Attorney.

UNITED STATES PATENT OFFICE

SUSANNA COCROFT HEADINGTON, OF NEW YORK, N. Y.

DEVICE FOR WAVING HAIR

Application filed December 5, 1928. Serial No. 323,906.

This invention relates to devices of the type that are used for imparting a wavy appearance to hair.

It is the general purpose and object of the invention to provide a device of this character which is simple in construction; which may be conveniently operated for the purpose of producing the desired wave-like effect in hair; and which is extremely efficient in operation.

10 While the device may be used for the production of what is known as a "water wave" and a "Marcel" wave, it is particularly adapted for the production of what is known as a "permanent" wave.

15 Referring to the drawings in which the device is illustrated Fig. 1 represents a perspective view of a complete device showing the cover and base in closed position; Fig. 2, a plan view of the device, showing the cover and the base in open or hair-receiving position; Fig. 3, a view in sectional side elevation of the device, showing the manner of applying the hair to the base member prior to clamping the cover member to the base member and closing the said members; Fig. 4, a transverse sectional view through the device, showing the same in closed position and illustrating the manner in which it operates upon the hair; and Fig. 5, a front elevation 25 of the said device.

The complete device illustrated herein comprises generally a transversely curved base member shaped to provide alternating U-shaped recesses and inverted U-shaped elevations, with heating means for said depressions and elevations, the said base member having a transversely curved insulated pad by means of which the device may rest upon the head of the user or patron during the waving operation; also a cover member which is detachably hinged at one edge to a corresponding edge of the base member and which is provided with rods adapted to enter the depressions on the base member, together with means for adjusting some of the said rods toward the base member, thereby to stretch the hair during the heat treatment. In addition, there are used with the device pads which 50 serve to maintain the hair moist and protect

the hair from injury by the heat applied to the base member.

Describing the parts referred to by reference characters, A denotes generally the operating part of the base member, and B, B' the pad. The base member A is preferably formed of metal, such as aluminum, having transversely curved downwardly extending end flanges 1, and side flanges 2. Fitted within seats 3 provided in said side and end flanges, is a transversely curved bottom plate 4, and secured to this bottom plate is the upper part B of the pad, such upper part being preferably a plate of bakelite, which is separated and supported from the plate 4 by 60 means of insulating spacers 5. Cemented or otherwise suitably secured to the under side of the plate B is the pad B', which may be of any suitable fibrous material.

The upper face of the base member A is provided with a plurality of inverted U-shaped or V-shaped ribs 6 with U-shaped depressions 7 provided therebetween. Between each end rib and the upwardly extending side flange 2 adjacent thereto is provided a shallow U-shaped depression 8.

Secured to one of the side flanges 2 is a handle 9, the said handle having a bore therethrough for the passage of a cord 10 containing electrical conductors 11 and 12 which extend into the interior of the member A, where they are connected with a suitable resistance formed into a heater 13 having portions extending into the ribs 6 and beneath the depressions 7 and 8.

85 The opposite flange 2^a is provided with a perforated lug 14 at each end thereof, which lugs are adapted to receive hinge lugs or projections on the cover member, which will now be described.

90 The cover member consists of a casing, indicated generally at C, the casing having a top 15, downwardly flaring sides 16, 17, and ends 18 having their lower edges transversely curved and adapted, when the cover is closed, to engage, or to substantially engage, the tops of the flanges 1 on the base member.

95 The cover wall 16 is provided with a handle 19 having secured thereto a spring clamp 20 which is provided at its lower end with a lug

21 adapted to snap into an opening provided therefor, but not shown, at the inner end of the handle 9. Projecting from opposite ends of the opposite wall 17 are hinge lugs 22 which are adapted to be inserted into the perforations in the lugs 14.

For convenience of description, the handle-carrying portions of the base and cover will be referred to hereinafter as the "front" of 10 each of these parts and the opposite portion or end of each will be referred to as the "rear".

23 denotes a rod which is mounted in the lower ends of the walls 18, adjacent to the 15 rear of the cover, and 23^a a rod which is mounted in the lower ends of the walls 18, adjacent to the front of the cover. These rods are so positioned that, when the cover is applied to the base and closed, the rods 20 will extend above the bottoms of the depressions 8. In addition to the rods 23 and 23^a, rods are provided to enter the U-shaped depressions 7 formed between the ribs 6. Two such rods 24 are shown, one for each depression 25 7; but it will be understood that the number of these rods will vary with the number of ribs and depressions therebetween. Each of the rods 24 is provided with reduced ends 24^a, which ends are mounted in slots 18^a provided in the walls 18, whereby the said rods are adjustable toward and from the bottoms of the depressions 7. For the purpose of moving the rods positively toward the bottoms 30 of these depressions, the cover is provided 35 with a pair of lugs 15^a each having a threaded bore in each of which is mounted a bolt 25, each having at its lower end a head 26 attached thereto and at its opposite end a thumb piece 27.

40 With the parts constructed and arranged as described, the operation will be as follows, assuming that the device is to be used for the production of a permanent wave:

The hair of the user or patron is parted and 45 the hair on one side of the part is lifted so that the base member may be applied with its rear side adjacent to the part. In order to secure the waver to the head, the base member has a wide tape D applied to the front 50 thereof by means of a bail D', the opposite end of the tape being provided with an adjusting buckle D², mounted in ribbon loops D³, the upper ends of which may be slipped over the upper ends of the lugs 14. By means 55 of the buckle, the tape may be adjusted so as to support the device comfortably upon the head of the wearer. A thin pad consisting of a strip of parchment or other suitable prepared paper 28 is applied to the tops of the 60 projections 6 on the lower member, as shown in Fig. 3. Over this is laid a second pad consisting of a piece of soft cloth 29 which has been saturated with water. The rear edge of the cloth is preferably corded, as 65 shown at 29^a. The hair 30, suitably treated

with the waving fluid, is then laid upon the cloth. The hinge lugs 22 are then inserted into the openings in the lugs 14 and the cover is closed. This closing movement draws the hair and the paper and cloth pads 70 upon which it is supported into the depressions 7 and 8. The corded edge of the cloth prevents the cloth from being drawn into the base beyond the top of the flange 2^a. When this corded edge engages the flange, 75 further closing movement of the cover member tends to stretch the hair by the action of the rods 23, 23^a and 24.

When the cover is entirely closed, the hair is clamped between the front edge 16^a of the 80 wall 16 and the top of the flange 2 therebelow; also between the bottom 17^a of the rear wall of the cover and the top of the flange 2^a. Then, if deemed necessary to stretch the hair further, the bolts 25 may be 85 adjusted to force the rods 24 downwardly in their slots.

In practice, the front ends of the cloth and paper pads are slitted so as to accommodate the handle 9 and the spring clamp 20. 90

The device described herein can be used for the production of a Marcel wave and also for the production of a water wave. When a water wave is to be produced, the paper strip 28 and the cloth pad 29 will be 95 omitted. Further, after a shampoo, the hair may be put into the waver and set into waves again.

Having thus described my invention, what I claim is:

1. A device of the character described comprising a base member having its upper face provided with alternating depressions and ribs, a cover for said base member having members adapted to enter the said depressions, the base member being transversely curved, a support for said base member, the said support comprising a transversely curved plate of insulating material, a pad applied to the lower surface of such plate, 105 and means securing the said plate to the base member, said means comprising spacers of insulating material between the base member and the plate, and means in said base member for heating the upper or operating 110 surface thereof.

2. A device of the character described comprising a base member having its upper face provided with alternating depressions and ribs, a cover for said base member having 120 members adapted to enter the said depressions, a support for said base member, the said support comprising a plate of insulating material, a pad applied to the lower surface of such plate, and means securing the said plate to the base member and for spacing the plate from said member, and means in said base member for heating the upper or operating 125 surface thereof.

3. A device of the character described com- 130

prising a base member having the upper surface thereof provided with upwardly projecting ribs and with depressions alternating with said ribs, the said member having an upwardly extending flange at the front and at the rear edge thereof, a depression being formed between each flange and the rib adjacent thereto, means carried by the said base member for heating the said ribs and depressions, a cover, and means for hingedly connecting one edge of said cover to the corresponding edge of said base member, the said cover having front and rear walls, means whereby the hair is pressed between the bottoms of the said front and rear walls of said cover and the tops of the front and rear flanges, and members carried by said cover adapted by the closing thereof to be projected toward the bottoms of the aforesaid depressions.

4. A device of the character described comprising a base member having the upper surface thereof provided with upwardly projecting ribs and with depressions alternating with said ribs, the said member having an upwardly extending flange at the front and at the rear edge thereof, a depression being formed between each flange and the rib adjacent thereto, means carried by the said base member for heating the said ribs and depressions, a cover and means for hingedly connecting one edge of said cover to the corresponding edge of said base member, the said cover having front and rear walls adapted to press the hair into engagement with the tops of the front and rear flanges, members carried by said cover adapted by the closing thereof to be projected toward the bottoms of the depressions on the base member, and means carried by the said cover for adjusting some of the last mentioned members toward the bottoms of the depressions with which they respectively cooperate.

5. A device of the character described comprising a base member having the upper surface thereof provided with upwardly projecting ribs and depressions alternating with said ribs, means carried by the said base member for heating the said ribs and depressions, a cover and means for connecting the cover to the said base member, members carried by said cover adapted by the closing thereof to be projected toward the bottoms of the depressions on the base member, and means carried by the said cover for adjusting one or more of the last-mentioned members toward the bottoms of the depressions with which they respectively cooperate.

6. A device of the character described comprising a base member having the upper surface thereof provided with upwardly projecting ribs and with depressions alternating with said ribs, the said member having an upwardly extending flange at the front and at the rear edge thereof, a depression being

formed between each flange and the rib adjacent thereto, means carried by the said base member for hingedly connecting the rear edge of said cover to the rear edge of said base member, the said cover having front and rear walls adapted to press the hair into engagement with the top of the front and rear flanges, and members carried by said cover adapted by the closing thereof to be projected toward the bottoms of the depressions on the base members, one or more of said members having its ends mounted in slots in the end walls of the cover, and means carried by the cover for engaging such adjustable member or members for moving the same toward the base member.

7. A device of the character described comprising a base member having the upper surface thereof provided with upwardly projecting ribs and depressions alternating with said ribs, the said member having an upwardly extending flange at the front and at the rear edge thereof, a depression being formed between each flange and the rib adjacent thereto, means carried by the said base member for heating the said ribs and depressions, a cover and means for hingedly connecting the rear edge of said cover to the rear edge of said base member, the said cover having front and rear walls adapted to press the hair into engagement with the top of the front and rear flanges, rods mounted in the end walls of the cover and arranged to register with the depressions on the base member, one or more of the intermediate rods having ends mounted in slots in the end walls of said cover, and means threaded through the said cover for pressing a rod or rods so mounted toward the bottom of the depression with which each of such rods cooperates.

8. A device of the character described comprising a base and a cover provided with cooperating wave-forming members, means for adjusting one or more of the wave-forming members with respect to a cooperating wave-forming member, said means including mechanism for holding said members fixed in any adjusted position and means for heating the hair while held by said members.

9. A device of the character described comprising a base member having the upper surface thereof provided with upwardly projecting ribs and depressions alternating with said ribs, means carried by the said base member for heating the said ribs and depressions, a cover, and means for connecting the said cover to the said base member, rods mounted in the end walls of the cover and arranged to register with depressions on the base member, one or more of the rods having ends mounted in slots in the end walls of said cover, and means for adjusting a rod so mounted toward the bottom of the depression with which it cooperates.

10. A device of the character described

comprising a base having wave-forming projections and depressions, a cover having wave-forming members cooperating with the wave-forming projections and depressions on the base, means for hingedly connecting the rear edges of the base member and cover, a handle applied to the front of the base, a handle applied to the front of the cover, and a spring clamp carried by one of the said handles and adapted automatically to engage the other handle, thereby to lock the cover in closed position.

11. A device of the character described comprising a base having wave-forming projections and depressions, a cover having wave-forming members cooperating with the wave-forming members on the base, means for hingedly connecting the rear edges of the base and cover, a handle applied to the front 15 of the base, a handle applied to the front of the cover, a clamp secured to the handle for the cover and having a depending spring adapted to engage the handle on the base, the latter handle and the depending spring portion of the clamp having the one a projection and the other a notch or recess for said projection.

12. In a device of the character described, the combination of a base having a rear upwardly extending flange and a front upwardly extending flange and provided with alternating wave-forming projections and depressions, means carried by the base member for heating the wave-forming portions thereof, 30 a shielding pad applied to the said flanges and projections, an absorbent pad applied to the top of the first mentioned sheet and having a corded rear edge, and a cover adapted to be hingedly connected to the rear of the base and having wave-forming members adapted to engage a layer of hair on top of the absorbent pad and to force such layer and the two pads into the depressions on the base member, the said cover having the bottom of its rear edge 35 adapted to clamp the hair and interposed pads between itself and the top of the rear flange on the base member, the front flange of the base member and the lower edge of the front wall of the cover member also being arranged to exercise a similar clamping effect when the cover is closed.

13. In a device of the character described, the combination of a base having a rear upwardly extending flange and a front upwardly extending flange and provided with alternating wave-forming projections and depressions, means carried by the base for heating the wave-forming portions thereof, a shielding pad applied to the said flanges and projections, an absorbent pad applied to the top of the first mentioned pad and having a corded rear edge, and a cover adapted to be hingedly connected to the rear of the base and having wave-forming members adapted to engage a layer of hair on top of the absorbent 55 60 65 70 75 80 85 90 95 100 105 110 115 120 125 130

pad and to force such layer and the two pads into the depressions on the base member, the said cover having the bottom of its rear edge adapted to clamp the hair and interposed pads between itself and the top of the rear flange on the base member, the front flange of the base member and the lower edge of the front wall of the cover member also being arranged to exercise a similar clamping effect when the cover is closed, and means for adjusting one or more of the wave-forming members of the cover toward the bottoms of the depressions in the base with which they respectively cooperate.

14. In a hair waving device, a member provided with alternate ribs and depressions, a cover for said member having means whereby it is detachably engaged therewith, rods carried by said cover adapted to engage in said depressions, and means whereby one of said rods may be adjusted with respect to said cover.

In testimony whereof, I hereunto affix my signature.

SUSANNA COCROFT HEADINGTON. 90
